Stove Company, Kansas City, Mo., a corpora-
tion of Missouri

Application March 19, 1942, Serial No. 435,259

5 Claims. (Cl. 126—73)

This invention relates to a heater designed for burning solid fuels and which consists of a casing provided with a fuel magazine equipped with flues for receiving gases evolved from combustion of the fuel, the gases being consumed in the flues along with smoke particles to provide a very high combustion efficiency.

Such magazines have been formed of opposed refractory slabs extending upwardly from the grate and spaced inwardly from the casing to define the flues along the entire height thereof, the refractory slabs being spaced apart and retained in position by refractory liners covering that portion of the casing intermediate the refractory slabs. Consequently flames resulting from the burning gases within the flues play directly upon metal surfaces and produce excessively hot spots throughout the height of the flues while the portions of the casing protected by the intermediate refractories remain much cooler with the result that the heater is of relatively short life. Regardless of this fact, such heaters have been popular for the reason that they provide for a sizeable charge of solid fuel, particularly of the less expensive grade so that the heaters operate at low cost over long periods with a single fuel charge.

It is, therefore, the principal object of the present invention to provide a heater of this character constructed for effecting substantially uniform heat distribution over the entire area of the casing, thereby avoiding hot spots at the flues and equalizing temperature of the metal to prolong life thereof and permit the exterior to be porcelainized or otherwise finished to improve the appearance thereof.

Other objects of the invention are to provide a flue structure that effects more efficient combustion of the gases through contact of the flames with highly heated refractory surfaces; to provide a free outlet and distribution of the evolved gases into the flues; to provide a simple and less expensive construction that may be manufactured at lower cost; and to provide a heater of the above character with refractories that are readily manufactured, and when assembled in the casing form the gas flues and protect the casing from direct contact of the flames resulting from the gases burning therein.

It is a further object to provide a structure adapted to both round and square types of heaters.

In accomplishing these and other objects of the invention, I have provided improved structure,

the preferred forms of which are illustrated in the accompanying drawings, wherein:

Fig. 1 is a vertical section through a heater embodying the features of the present invention.

Fig. 2 is a cross-section on the line 2—2 of Fig. 1.

Fig. 3 is a horizontal section on the line 3—3 of Fig. 1.

Fig. 4 is an enlarged perspective view of one of the refractories which form the gas flues.

Fig. 5 is a horizontal section through a rectangular type heater embodying the features of the present invention.

Fig. 6 is a perspective view of one of the refractories employed in the heater illustrated in Fig. 5.

Referring more in detail to the drawings:

1 designates a heater embodying the features of the present invention and which includes a substantially cylindrical sheet metal casing or body 2 having a bottom 3 supported from the floor by legs 4. The top of the casing is enclosed by a dome 5 having an annular flange 6 encircling a shoulder 7 to receive the upper edge of the casing 2 on which it is supported. The dome 5 also has an inwardly converging perimetrical wall portion equipped with a lateral flue outlet connection 8 at one side and a fuel inlet opening 9 at the other. The inlet opening 9 is disposed in an inclined plane and is normally closed by a door 10.

Supported within the interior of the casing 2, and spaced above the bottom 3 to form an ash-pit 11, is a circular ring 12, having a depending annular flange 13 secured to the inner face of the casing. The ring 12 is of sufficient width to form an annular ledge 14 for supporting refractories within the heater casing as later described. The inner edge of the ring is offset downwardly as indicated at 15 to form an annular shoulder 16 to seat a grate 17. The inner marginal edge of the ring which encircles the grate is provided with notch-like openings 18 through which combustion supporting air passes from the ash-pit 11 upwardly through the fuel contained in the fuel magazine of the heater, as later described. The grate 17 also has air inlet openings 19. The grate may be provided with a central opening 20 closed by a shaker plate 21 slidably supported under the grate on guides 22. The shaker plate is manipulated by means of an arm 23 that projects in convenient reach of an operator when the door 24 of the ash-pit is opened. The door 24 is of ordinary construction and is provided with an air inlet opening controlled by a damper 25 as in usual heater practice.

Supported upon the ledge 14, preferably at opposite sides of the casing, is a plurality of tiered hollow refractory blocks 26, one of which is best illustrated in Fig. 4. As will be noted in Fig. 4, the hollow refractory blocks 26 include an arcuate rear wall 27 having an exterior surface 28 conforming in radius to the radius of the heater casing so that the refractories fit closely against the inner surface of the casing and transmit heat thereto. The opposite walls 29 of the refractories are relatively flat and are spaced from the rear wall 27 by radial end walls 30 and 31 to form flue portions 32 therebetween and defined by the arcuate inner surfaces 33 of the walls 27, flat inner surfaces 34 of the walls 29, and curved surfaces 35 and 36 of the end walls 30 and 31. The upper and lower edge faces 37 and 38 of the refractories are preferably flat so that when the refractories are tiered to form a flue they closely engage and prevent leakage of gases through the joints thereof.

In order to provide gas inlets from the magazine of the heater into the respective flues, the front wall at the upper edge of each refractory is provided with an elongated notch 39 having inclined bottoms 40 extending transversely across the wall and sloping upwardly in the direction of the flues. The lower edges have somewhat similar notches 39' having top faces 40' sloping from the lower front edge upwardly in substantially parallel relation with the bottoms 40 of the upper notches, so that when the refractories are placed in position one on the other the notch in the lower face of an upper refractory cooperates with the notch in the top of a lower refractory to form a series of nozzle-like openings for discharge of gases evolved within the fuel magazine into the flues and in impingement with the inner faces of the outer walls at points above the joints between the blocks.

Interposed between the flue forming refractories are substantially arcuate-shaped refractories 41 and 42 which cooperate with the arcuate wall portions 27 of the flue refractories to line the heater casing completely and protect it from direct contact by flames resulting from combustion of fuel.

The sides 43 and 44 of the arcuate refractories conform to the angle of the end walls 30 and 31 so that they abut thereagainst and provide substantially gas-tight joints therebetween and form an interlock with the flue refractories to retain the refractories in position and in close contact with the inner surface of the heater casing. A sufficient number of refractories is superimposed upon each other to extend to the upper rim of the casing as shown in Figs. 1 and 2, but the refractories terminate short of the dome 5 to provide outlets 45 and 46 for the respective flues into the dome 5 for discharge of spent products of combustion by way of the flue outlet connection 8. With this arrangement the casing is lined completely with refractory material and a relatively large magazine is provided so that a sizeable charge of solid fuel may be discharged into the magazine through the opening 9 to produce a prolonged heat.

If, for some reason, the refractories should tend to crack, for example because of uneven expansion and contraction, the refractories are provided with weak points on which the fractures are caused to occur, thereby controlling the place of fracture and preventing disruption of the lining. The weak points are preferably formed by providing the front and rear walls of each re-

fractory with notch-like grooves 41' located vertically at the mid portions thereof. To assure a clean break squarely through the refractories, smaller notches 41'' may be formed across the edges of the walls, as shown in Fig. 4.

In operation, a fire is kindled upon the grate and the magazine is charged with fuel through the opening 9, substantially to the top of the refractories. Upon starting of the fire, draft is effected through the draft opening of the ash-pit, through the openings in the grate, and through the spaces between the fuel to the flue connection 8. A portion of the air is also drawn through the slot-like openings between the refractories which portion moves upwardly through the flues and is discharged through the flue connection along with the air drawn through the body of the fuel. The fire burns from the bottom, coking the upper fuel and driving off gases, which are drawn through the slot-like openings into the flues and are combusted with the aid of air moving therethrough so that flames play on the inner surfaces of the flues and the heat thereof is transmitted substantially uniform throughout the relatively large bodies of the refractories to the casing to heat the air surrounding the periphery of the heater.

The wall portions 27 of the flue forming refractories are of sufficient thickness to protect the metal of the casing and prevent excessively heated areas. The outer surface of the heater is, therefore, maintained at a lower and substantially uniform temperature so that it has longer life and the exterior thereof may be covered with porcelain or otherwise finished to improve the appearance.

The form of the invention illustrated in Fig. 5 is similar to that illustrated in Figs. 1 to 4 inclusive, however, it is carried out in a square type of heater, that is, the casing 48 is of rectangular cross-section and the flue refractories 49 are disposed in the corners thereof and spaced apart by slab-like refractories 50. The corner refractories have substantially angle-shaped outer walls 51 and biasly arranged inner walls 52 connected to the terminal ends of the outer walls 53 and 54 preferably having flat faces abutting the side edges of the refractories 50. The walls 52 have the horizontal front edges thereof provided with notches 55 similar to the notches 39 in the refractories previously described.

The operation of the form of the invention shown in Fig. 5 is substantially that above described with the exception that the evolved gases are discharged through the notch-like openings at the respective corners of a substantially rectangular shaped magazine. The flames burn within the triangular-shaped flues to heat the angular walls thereof so that the heat is distributed substantially uniformly to the metal of the casing in proportion to that transmitted by the flat refractories 50. Thus the casing is maintained at substantially constant uniform temperature over the entire surface thereof.

From the foregoing it is obvious that I have provided a heater structure having all the advantages of the conventional magazine type heater with the added advantage of better and more efficient combustion, more uniform heat distribution, and longer life.

What I claim and desire to secure by Letters Patent is:

1. In a heater of the character described, a refractory flue comprising hollow refractory blocks arranged in a tier, each block having inner

and outer wall portions spaced from each other by integral side wall portions and positioned in the tier with the ends of the blocks in abutment, said inner wall of the blocks having an elongated horizontally arranged notch-like opening in an edge extending transversely of the flue and having an upwardly inclined horizontal portion cooperating with a like portion on the adjacent edge of an adjacent block in the tier to form an upwardly and inwardly directed gas inlet whereby flames resulting from combustion of gas passing through the inlets are guided into impingement with the outer refractory walls at a point above joints between abutting ends of the outer walls.

2. A heater including a casing having a vertical wall through which heat is transmitted, hollow refractory blocks arranged in tiers with the tiers of blocks spaced apart within the wall of the casing, each block having inner and outer wall portions spaced from each other by integral side wall portions, said outer wall portions of the refractory blocks being arranged in substantial contact with the wall of the casing and with the ends of the outer and side wall portions of the blocks resting one upon the other to provide vertical flues having refractory surfaces on all sides thereof for aiding in burning gases in said flues to heat the wall of the casing, said inner walls of the blocks having elongated notches in horizontal edges thereof extending substantially across the width of said flues and having horizontal portions cooperating with inclined edge portions extending upwardly from the lower edge of the adjacent block in the tier to direct the burning gases into impingement with the outer walls of the blocks at a point above the joint between said outer walls of the blocks, and slab-like refractories substantially conforming in shape to the wall of the casing intermediate said tiered blocks and having side edges closely abutting the side walls of said tiered blocks to cooperate with the tiered blocks in forming a refractory lining for the wall of the casing and a fuel-containing magazine for the heater.

3. A heater including a casing having a vertical wall through which heat is transmitted, hollow refractory blocks arranged in tiers with the tiers of blocks spaced apart within the wall of the casing, each block having inner and outer wall portions spaced from each other by integral side wall portions, said outer wall portions of the refractory blocks being arranged in contact with the wall of the casing and with the ends of the outer and side wall portions of the blocks resting one upon the other to provide vertical flues having refractory surfaces on all sides there-

- of for aiding in burning of said gases in said flues to heat the wall of the casing, said inner walls of the blocks having elongated notches in horizontal edges thereof extending substantially across the width of said flues and having horizontal portions cooperating with inclined edge portions extending upwardly from the lower edges of the adjacent blocks in the direction of the flue to direct the burning gases out of contact with the joint between said outer walls of the blocks, and slab-like refractories substantially conforming in shape to the wall of the casing intermediate said tiered blocks and having side edges closely abutting the side walls of said tiered blocks to cooperate with the tiered blocks in forming a refractory lining for the wall of the casing and a fuel-containing magazine for the heater, said slab-like refractories having less thickness than the inner to outer depth of the tiered blocks so that the inner faces of the inner walls of the blocks are out of plane with the inner surfaces of the slab-like refractories to facilitate entrance into the flues of gases which are evolved in the magazine.
4. In a heater including front, rear, and side walls forming a casing of substantially rectangular cross section and through which heat is transmitted, hollow refractory blocks arranged in tiers in corners of the casing and having angular outer wall portions in substantial contact with the corners of the casing and having diagonal inner wall portions connected with the outer wall portions by side wall portions, said outer and side wall portions of the blocks resting one upon another to provide vertical flues having refractory surfaces on all sides thereof for aiding in burning of gases in said flues to heat corner portions of the casing, said diagonal inner walls of the blocks having elongated notches in horizontal edges thereof extending substantially across the width of said flues and having lower edges upwardly inclined in the direction of the flues and cooperating with said notches of the next adjacent block to provide passageways into said flues for directing flames in impingement on the outer walls of the blocks at points above the joint between said outer walls.
5. In a heater of the character described, a hollow refractory block having inner and outer walls connected by side walls, said front wall having horizontal notches in the upper and lower edges with the lower of said notches having an inclined deflecting surface extending upwardly from the front lower edge and terminating at the inner surface of the inner wall above the corresponding edge of the outer wall.

EDWIN ESSON.
